UNITED STATES PATENT OFFICE.

DANIEL G. BUTTS, OF NEW ORLEANS, LOUISIANA, ASSIGNOR TO IVORY CARTER COMPANY, OF NEW ORLEANS, LOUISIANA, A CORPORATION OF LOUISIANA.

HOSEIERY-SUPPORTER.

1,248,804.

Specification of Letters Patent.

Patented Dec. 4, 1917.

Application filed June 22, 1915. Serial No. 35,580.

To all whom it may concern:

Be it known that I, DANIEL G. BUTTS, a citizen of the United States, residing at New Orleans, in the parish of Orleans and State 5 of Louisiana, have invented certain new and useful Improvements in Hosiery-Supporters; and I do hereby declare the following to be a full, clear, and exact description of the same, reference being had to the accompanying drawings, forming part of this 10 specification, and to the figures and letters of reference marked thereon.

The present invention relates to well known types of hosiery supporters which 15 embody in their construction a webbing or strap upon which there is mounted a button member and a loop member, the loop member having an aperture therein for the reception of the button. This aperture is 20 larger at one end than at the other whereby the head of the button may be passed through the opening and the shank of the button drawn into the smaller end. The button and loop are adapted to coöperate 25 either for attaching the supporter to the hosiery or for connecting the ends of the supporter after the same has been passed around the limb of the wearer.

The objects of the invention are to provide 30 a supporter which will be less liable to injury should the same, when lying on the floor, be stepped on, and which will not only provide a secure attachment to the hosiery but will prevent injury to the latter even 35 when the hosiery is of the finest quality. A further object of the invention is to provide for a flexibility and softness of action between the parts of the attaching devices which will materially add to the comfort of 40 the wearer.

Referring to the accompanying drawings:—

Figure 1 is a perspective view of a supporter designed for gentlemen's wear with 45 the attaching members separated so as to illustrate their construction.

Fig. 2 is a section through the pendent webbing and button member carried thereby.

Fig. 3 is a section through the shank of a 50 button showing the cross sectional shape of the shank and contour of the opening in the button plate in which the shank is mounted.

Fig. 4 is a section in a plane at right angles to Fig. 2.

Like letters of references in the several 55 figures indicate the same parts.

In the form of supporter illustrated in the drawings the letter A indicates elastic webbing adapted to encircle the limb of the wearer, B a loop member adjustably mounted on the web A through the medium of a flat slide C. D is a button member secured to the opposite end of the elastic webbing and adapted to support the pendent webbing ends E, one of which carries a button 60 member F and the other a loop member G. The button members D and F are in general characteristics similar, that is to say, they embody plates provided with elongated openings for the webbing, indicated at d, f, 65 respectively, said openings being located near the edges of the plates, and the plate D in addition is provided with a bottom webbing aperture through which the pendent webbing ends are passed whereby they are 70 supported. Each of the plates D and F are preferably of concavo-convex formation at the center and are provided with a central button shank opening which is of non-circular formation. This opening, indicated at 75 D' and F', is preferably elongated or formed with major and minor diameters, the major diameter extending generally in the direction of the strain to which the button is subjected when the supporter is in use, that is 80 to say, substantially horizontally in the plate D and vertically in the plate F.

The buttons employed in both instances are soft rubber buttons. They are provided with a base portion H which is seated in 90 the concave portion of the plate and a head which is of such size that it may pass readily through the button opening in the plate. Said head is indicated at H', and between the head and base there is a shank 95 H² having its base portion or part adjacent the button base made of a cross sectional shape which will fit and substantially fill the aperture in the plate. The button is inserted from the back of the plate and is 100 retained in position by the webbing, which latter passes through the edge openings of the plate and behind the base of the button. The pendent loop or end has one reach passed through the upper opening from the 105 front side of the plate, thence down behind the button base and forwardly through the lower opening. The other reach of the web-

bing passes up behind the first mentioned reach and the two reaches are sewed together at I thus securely retaining the button in place and fastening the plate firmly to the 5 webbing.

In the construction of the parts described, it will be noted that all of the semi-rigid members are flat, or substantially flat, with no rigid projections whatsoever, and these 10 parts are conveniently or preferably made of celluloid while the button is made of soft rubber, with the result that injury to the finest fabric hosiery is effectually prevented, and there is little or no danger of any of 15 the parts being broken or bent permanently out of shape by being stepped upon when lying on the floor. Experience shows that a large proportion of hosiery supporters are destroyed or injured so as to be unsatisfactory through accidents of the character 20 mentioned.

The construction of the buttons in the form illustrated and described is advantageous inasmuch as they may be made in 25 strips or gates and severed from each other without the necessity of further finishing. This results in a material economy in construction and is advantageous in the supporter itself, inasmuch as a square base is 30 provided which will assist in holding the button firmly in position on the plate. By

35 preventing the rotation of the button in the plate the loop member is held in proper alignment with the plate but at the same time it may be flexed or twisted in either direction and when freed from pressure tending to twist the same will return to its 40 normal position. The elongation transversely of the shank is always in a direction which is in the line of strain and the soft rubber of the shank will therefore be of ample strength to resist breakage even though the shank is comparatively narrow in the other direction.

45 I claim:

In a garment supporter the combination of a plate of rust-proof sheet material, having a central button opening and symmetrically placed webbing openings, said central opening having a major and a minor 50 diameter, of a soft rubber button having a head, a shank and a base, each of which has a major and a minor diameter, the major diameter in each case being of the same length as the major diameter of said button opening, and the minor diameter of said shank being such as to snugly fit the minor diameter of the central opening, whereby the button is prevented from turning with respect to the plate.

55 DANIEL G. BUTTS.
